United States Patent Office.

JAMES MONTGOMERY, OF SING SING, NEW YORK.

Letters Patent No. 98,089, dated December 21, 1869; antedated December 17, 1869.

IMPROVEMENT IN STEAM-GENERATORS.

The Schedule referred to in these Letters Patent and making part of the same

To all whom it may concern:

Be it known that I, JAMES MONTGOMERY, of Sing Sing, in the State of New York, have invented a new and useful Improvement in Steam-Generators; and I do hereby declare that the following is a full, clear, and exact description of the same, reference being had to the annexed drawing, making part of this specification, in which—

Figure 1 is a central sectional elevation of my improved generator;

Figure 2 is a transverse section, on line $z z$ of fig. 1;

Figure 3 is a central section of the grate, showing also its supports as secured to the shell of the generator, and an end view of the shaft upon which the worm is secured which rotates the same;

Figure 4 is a transverse section, showing a portion of the grate, a portion of the upper tube-sheet, and a portion of the lower tube-sheet;

Figure 5 is a plan view of a portion of the grate, showing also a segment of the gear upon its periphery, and also the worm, by which motion is given to such grate;

Figure 6 is a plan view of a group of generators, as arranged for marine engines;

Figure 7 is an elevation of the same, when similarly arranged, with a smoke-pipe in the centre of the group for the escape of the products of combustion;

Figure 8 is an end elevation of a portion of the elevators which feed the coal into the hopper, formed around the tops of the generators; and

Figure 9 is a side elevation of the same, showing also the belt and pulley which drive the same.

Corresponding letters represent corresponding parts in the several figures.

It is a well-known fact that steam-generators, as at present constructed, are deficient in their arrangements for the perfect combustion of the gases arising from the burning fuel.

One of the objects of my invention is to provide a remedy for this defect, and, to this end, I propose to construct a generator in such a manner as to concentrate all of the gases to one point, and conduct them to a chamber, the lower surface of which should be lined with fire-bricks or some equivalent material, which, owing to the high temperature which it is capable of attaining, will ignite such gases as they come in contact therewith, and thus prepare them to enter the tubes or flues in a condition of flame, or of perfect or nearly perfect ignition.

To produce this condition of the gases, I propose to place in the centre of the grate an outlet, through which all the gaseous products of combustion must pass in escaping from the furnace, and from which they are to be delivered into a combustion-chamber,

where they will be thoroughly mixed with a sufficient quantity of oxygen for the support of combustion, prior to being admitted to the tubes.

This invention, therefore, relates to that class of steam-generators known as "vertical generators;" and

It consists in the construction, combination, and arrangement of its parts, as will be more fully explained hereinafter.

A, in the drawings, represents the shell of the generator, which may be of iron, steel, copper, or any other suitable material, and of any thickness required to give the necessary strength. The form of this generator, in its cross-section, may be cylindrical, octagonal, or of any other desired form, its upper end being dome-shaped, and terminating in an uptake for the passage of the products of combustion, as shown in fig. 1.

Within this outer shell, and at such a distance from it as to leave a suitable water-space, there is to be placed another shell, A', which is to be suspended to the base of the crown of the furnace, and which is to extend down to a point about midway of the length of the flues. This sheet is designed to cause a circulation of the water from the upper to the lower portion of the generator, the water and steam passing up from the lower portion of the generator, and from among the tubes or flues, over the convex portion of the upper tube-sheet to the space between the fire-box and this sheet or diaphragm, and to the space above such fire-box, where the steam becomes separated from the water, which, owing to the difference of temperature between the outer and inner portions of the generator, will cause a downward current of water to be constantly kept up through the space between the outer sheet A and the inner sheet A' of this portion of the generator.

The consequence of the above-described arrangement of these parts will be to carry the more highly-heated portions of the water down to, and cause them to mingle with those particles in the lower portion of the generator, which are at a lower temperature, and thus, to a great extent, cause an equalization of temperature throughout the whole of the generator and its contents.

Another advantage to be derived from this arrangement is, that the sediment or foreign matter which is held in suspension by the water, will, by this action, be carried down to and over the concave surface of the lower tube-sheet, and deposited in the receptacle G', arranged for its reception, as will be more fully described hereinafter.

B represents a coal-hopper or reservoir, which is to be arranged around or upon the upper portion of the generator, substantially as shown in figs. 1 and 7 of the drawings, it being my intention to have this hop-

per always supplied with coal, so that as the coal upon the grate burns away, its place shall be supplied by coals from this hopper or reservoir.

C C represent chutes or passages from the hopper B to the fire-chamber, of which there may be one or more, as circumstances may require, they being so arranged as to deliver the coals direct from the hopper B to the revolving grate D, as shown in fig. 1.

D represents the grate upon which the fuel rests, it being constructed as shown in figs. 2, and 5, and 6, where it will be seen that it is to be provided with gearing or cogs upon its periphery, which are to be acted upon by a worm-wheel or a screw for the purpose of giving a rotary motion to it. The manner of constructing the grate is as follows: In its centre there is to be an opening of sufficient diameter to admit of the passage through it of the neck formed upon the upper end of the upper sheet of the chamber D³. Immediately outside of this opening there is to be placed a ring, outside of which there is to be a space, concentric with such ring, which is one of a series, through which the ashes fall to the ash-pit. Outside of this space there is to be a series of rings and spaces, sufficient in number to make the grate of any required diameter, while to the outer ring there is to be attached a gear-wheel or segments of such a wheel, or such gear may be formed upon the outer ring, as preferred, the object being to afford the means of rotating the grate, as above described.

D¹ represents the fire or combustion-chamber, which, as shown in fig. 1, is to be arranged in the upper portion of the generator, and of which there may be one or more. Where more than one are used, they are to be arranged one above the other, and have a common outlet or connection with the chamber D³, above the upper tube-sheet.

D² represents the passage through which the products of combustion pass from the combustion-chamber to the tubes or flues. It is to be formed upon the upper portion of the plate which divides the combustion-chamber from the chamber above the upper tube-sheet.

D³ represents a chamber, which is located between the combustion-chamber and the upper tube-sheet, into which the heated products of combustion pass, preparatory to entering the tubes or flues. The lower sheet of this chamber is the upper tube-sheet, while its upper boundary is the sheet to which the neck which forms the passage D² is secured.

E E represent a series of vertical tubes, which extend from the upper to the lower tube-sheet, to each of which one of their ends is secured. There may be any number of rows of these tubes, limited only by the diameter of the generator, and they may be arranged concentric to each other, or in any other suitable manner.

F represents a chamber, which is to be within the lower portion of the generator, and immediately below the tubes or flues, it being for the reception of the ashes and cinders, which pass down through such tubes, and also for the purpose of allowing a free passage of the products of combustion from the tubes to the space H, between the outer surface of the boiler and the casing which surrounds it.

G represents a water-vessel or reservoir, which is to be attached to the central portion of the lower tube-sheet, from which it extends downward for any required distance, its lower and outer end being covered by a cap, which is to be bolted thereto, so that it may be removed for cleaning out the same. The object of this receptacle is to provide a suitable place for the deposit of the foreign substance which is to be found in all ordinary kinds of water, and to locate such receptacle at such a point as to facilitate the reception of such sediment, without bringing the same in contact with the most highly-heated portions of the generator.

H represents a chamber, which is formed by the shell of the generator, and a casing, H', which surrounds, and is concentric, or nearly so, with the same. This chamber is designed to receive the products of combustion from the chamber F, after the greater portion of their heat has been absorbed by the water within the generator, and conduct them around the outside of, but in contact with such generator, to and around the steam-dome, and thence into the atmosphere.

H' represents the jacket or casing above alluded to, which is to surround the generator, and is to be of such dimensions as to leave the required space between it and such generator for the passage of the products of combustion. This casing extends some distance below the bottom of the generator, its lower end being provided with a head for the purpose of giving the proper direction to the gases from the tubes.

I represents the steam-pipe, which conducts the steam from the generator to any desired locality, it passing for some distance through the uptake, for the purpose of preventing condensation, and also for the purpose of superheating the steam, should the temperature of the escaping gases at any time be sufficient for that purpose.

K represents a worm or screw, which is to be arranged upon the side of the generator, in such a manner as to work into the rach K² of the grate.

K¹ represents the shaft upon which the worm is to be secured, which shaft is to be supplied, upon one of its ends, with a wheel for rotating it, either by hand or machinery. The arrangement of these devices, together with the means of securing them to the generator, are clearly shown in figs. 2 and 3 of the drawings.

K² represents the gear, which is to be attached to the grate, for the purpose of giving a rotary motion to the same.

It is apparent that when it is desirable to place these generators upon a vessel, they may be arranged in groups, as shown at figs. 6 and 7, and so that they may all be fed from a common or from separate hoppers or reservoirs, and the rotary movement of these grates be derived from the same or separate shafts, as circumstances may require.

Whether such generators are used singly or in groups, I propose to attach to the grate a scraper, to be moved thereby, that shall cause any ashes that would otherwise lodge upon parts upon which it bears, to be removed and allowed to fall down through the tubes.

The generator is to be provided with the necessary blow-cock, which may be secured thereto in any suitable position, and also with a safety-valve, which may, if preferred, be attached to the steam-pipe I.

Having thus described my invention,

What I claim, and desire to secure by Letters Patent, is—

1. The combination of the hopper B, chutes or passage C, and generator A, substantially as shown and described.

2. The concavo-convex flue-sheets, substantially as shown and described.

3. The combination of the combustion-chamber D¹ passage D², and chamber D³, substantially as shown and described.

4. The rotating grate D, arranged in the upper portion of the generator, substantially as shown and described.

5. The arrangement of the deflecting or guiding-plate A', with reference to the chamber D³ and the combustion-chamber D¹, substantially as shown and described.

6. The arrangement of the chamber D³, with reference to the tubes or flues E and the chamber F, substantially as shown and described.

7. The combination of the reservoir G with the tube-sheet of generator A, substantially as shown and described.

8. A steam-generator, combining in its construction a hopper or reservoir for coals arranged around its upper end, chutes for conducting the coals to the grate, a rotating grate arranged above the tubes, a chamber above and below the tubes, and a reservoir attached to the central portion of the lower tube-sheet

for the reception of the sediment, substantially as shown and described.

In testimony whereof, I have signed my name to this specification, in the presence of two subscribing witnesses.

JAMES MONTGOMERY.
